UNITED STATES PATENT OFFICE.

GEORGE I. DICKEY, OF TOLEDO, OHIO.

TENT.

Application filed February 4, 1924. Serial No. 690,380.

My invention has for its object to provide a tent supporting frame which is so constructed that the center or central poles may be eliminated, thus greatly increasing the available space within the tent, and also which is so constructed that the tent may be easily erected.

The invention may be contained in tents of different forms. To illustrate a practical application of the invention, I have selected a tent of the palmetto type, or form, as an example of tents containing my invention and shall describe it hereinafter. The tent selected is shown in the accompanying drawings.

Figure 1 of the drawings illustrates a section through the tent showing the tent in the process of erection. Fig. 2 is a sectional view of the tent showing the tent erected and the walls stretched. Fig. 3 is a sectional view taken on the line 3-3 indicated in Fig. 2. Fig. 4 is a sectional view taken on the line 4-4 indicated in Fig. 3. Fig. 5 is an enlarged view showing parts of the construction folded. Fig. 6 is a sectional view taken on the line 6-6 indicated in Fig. 5.

The tent is formed of canvas having the top and side walls 1. It is also, preferably, provided with a floor 2. In order to sustain the walls of the tent, jointed upright members 3 are located in the corners of the tent. The lower parts of the upright members 3 are preferably located in pockets 4 formed in the corners, and so as to hold the lower parts of the upright members when the tent is in a more or less collapsed condition.

The upper ends of the uprights are connected together by a means for distending the uprights and at the same time rendering the walls of the tent taut and smooth. To thus spread the walls of the tent, the upper ends of the uprights, which are located in the upper corners of the side walls of the tent, are connected by diagonally disposed jointed members and an element is located between the jointed members and the peak of the tent. In the form of tent shown the members 5 are pivotally connected to thimbles 6 and by a knife-blade joint 16 to the cross-shaped channeled member 7, and the screw 8, which sockets into the hub of the disc 9, is threaded through the cross-shaped member 7. The members 5 thus form links between the cross-shaped member 7 and the thimbles 6. The thimbles 6 are located on the upper ends of the members 3 and the

screw 8 extends to the disc 9 located in the peak of the tent. As the cross-shaped piece 7 is forced down against the elasticity of the fabric by forcing the screw against the peak, 60 the tent walls are distended until the fabric is rendered taut.

In order to render placement of the distending means easy in the erection of the tent, and in order that assemblage of the frame may be readily performed, I have provided a means for holding the links 5 partially distended to support the corners in a temporary position, in order that the tent may be easily entered for the purpose 70 of erection. To thus hold the links 5 temporarily distended, a second channeled cross-shaped member 10 is also located on the screw 8 and is located below the cross-shaped member 7 so as to engage the links 5. The cross-shaped member 10 is provided with the channels 11 in which the links 5 may be located, particularly at the outer ends of the arms of the member 10. The angle at which the member 10 will hold the links 5 will depend upon the position that the members 7 and 10 are located relative to each other on the screw 8. Thus, the distending means 80

5 placed in the ends of the channels formed in the cross-shaped member 10. The two cross-shaped members 7 and 10 may be then placed in any desired position relative to each other and in any desired position on the screw 8 to produce the desired temporary spreading of the top of the tent. The upper end of the screw 8 is then stepped into the hub of the disc 9 and the top of the tent is raised. If desired, in order to hold the top of the tent in its raised position, a pole 95 may be connected to the lower end of the screw. If the top of the tent has been stayed by ropes, the tent will be sustained in its temporary raised position. The upper parts of the jointed members 3 may then be inserted in the lower parts located in the pockets 4, and the thimbles 6 may be placed upon the upper ends of the parts 3. If a pole has been inserted between the lower end of the screw and the floor of the tent, it may be withdrawn and the screw rotated to cause distension of the corners and of the uprights, 100 to render the walls taut and smooth.

In order that the screw 8 may be easily rotated, it may be provided with a crank 110 handle 12, and upon operation of the crank handle, the cross-shaped member 7 will be

lowered, thus causing the links 5 to push out the thimble 6 and consequently the upper ends of the uprights 3. In order to provide an easy connection with the pole for temporarily supporting the tent, the crank handle may be provided with a hole 13 into which a pin 14 located in the end of the pole 15 may be inserted.

In taking the tent down, the peak and consequently the distending means may be released until the links 5 are supported by the cross member 10, and the pole 15, which may be an awning pole of the tent, may be inserted in position to temporarily sustain the distending means. The thimbles may then be removed from the ends of the members 3 and the members disjointed. Thereupon the tent may be lowered by withdrawing the pole 15.

When the tent has been taken down, the distending member may be folded by folding the links 5 together. This may be done by rotating the cross-shaped member 10 so that the arms of the cross member 10 will be located between the links 5, as shown in Figs. 5 and 6.

I claim:

1. In a tent, a distending means having parts extending inwardly from the corners of the tent, a member hingedly connecting the said parts at the center of the tent and having means located below the member for engaging the parts for limiting the downward swinging movement of the outer ends of the parts that engage the corners of the tent, a compression member located between the first named member and the peak of the tent for maintaining the top and sides of the tent distended and connected to the second named member.

2. In a tent, a distending means having parts extending inwardly from the corners of the tent, a member hingedly connecting the said parts at the center of the tent and having a second adjustable member located below the member for engaging the parts for limiting the downward swinging movement of the outer ends of the parts that engage the corners of the tent, a compression member located between the first named member and the peak of the tent for maintaining the top and sides of the tent distended and adjustably connected to the second named member.

3. In a tent, a distending means having parts extending inwardly from the corners of the tent, a member for hingedly connecting the said parts at the center of the tent,

a compression sustaining element adjustable as to its length located intermediate the said member and the top of the tent for adjustably forcing the top and the said member apart for stretching the top and the sides of the tent, a second member located below the first named member and connected therewith and below the hingedly connected ends of the said parts for supporting the hingedly connected parts in an outwardly extending direction.

4. In a tent, a distending means having parts extending inwardly from the corners of the tent, a member connecting the said parts at the center of the tent to limit the downward movement of the parts relative to the corners of the tent, a second member connected to the first member for maintaining the parts temporarily distended, an adjustable element located intermediate the first named member and the top for holding the joints of the said parts downward by the tension of the top.

5. In a tent, a distending means having parts extending inwardly from the corners of the tent and hingedly jointed together in the central part of the tent, a threaded rotatable member located intermediate the top and the joint for forcing the joint downwards and the top upwards and distending the corners, a member connected to the threaded rotatable member for supporting the parts temporarily distended.

6. In a tent, a distending means having parts extending inwardly from the corners of the tent and hingedly jointed together in the central part of the tent, a threaded rotatable member located intermediate the top and the joint for forcing the joint downwards and the top upwards and distending the corners, a member connected to the threaded rotatable member for supporting the parts temporarily distended, a means connected to the threaded means for temporarily supporting the distending means in the top of the tent.

7. A device of the character described comprising a central clamp having a plurality of arms pivoted thereto for radial adjustment, said clamp serving to bind said arms against movement from their positions of radial adjustment, legs pivoted to the outer ends of said arms, and a vertically adjustable tent top supporting member movable through said clamp.

In testimony whereof, I have hereunto signed my name to this specification.

GEORGE I. DICKEY.
